TYPEWRITING MACHINE

Henry Joseph Hart, West Hartford, Conn., assignor to Royal Typewriter Company, Inc., New York, N. Y., a corporation of New York

Application December 21, 1938, Serial No. 247,079

2 Claims. (Cl. 197—110)

This invention relates to typewriting machines and more particularly to line-lock mechanism, that is, mechanism for preventing type bar operation after the typewriter carriage has reached the end of a typed line as determined by the setting of carriage travel limiting means such as a margin stop.

It is usual to provide typewriters with mechanism for automatically locking the type bars or key levers against operative movement when the carriage approaches or reaches the end of its travel in letter spacing direction. One purpose of providing such mechanism is to prevent piling or superimposed type impressions at the end of a typed line after margin fixing mechanism has functioned to prevent further letter spacing movement of the carriage. Line lock mechanism heretofore known and now used commercially functions efficiently when the key lever depressed just prior to the actuation of the mechanism has been returned all the way or substantially all the way to its normal or elevated position before any other key lever has been depressed.

An object of the invention is to provide simple and efficient mechanism of the kind referred to adapted to effect certain and positive locking of printing instrumentalities such as type bars or key levers when the carriage reaches the end of its normal letter spacing movement.

Another object is to provide mechanism of the character referred to adapted to function when the carriage reaches the end of its letter spacing travel to positively lock key levers against being depressed or otherwise actuated even though the key lever actuated just prior to the carriage's reaching the end of its travel has not returned to its retracted or normal position.

More specifically, an object is to provide line-lock mechanism actuated in response to carriage travel, the arrangement being such that, with the carriage positioned one letter space away from its limit of travel in letter space direction, depression of any one of the key levers will effect movement of the carriage through the remaining letter space and will positively lock the other key levers against being depressed even though the depression key lever is held depressed.

Other objects will become apparent from a reading of the following description, the appended claims, and the accompanying drawing, in which:

Figure 1 is a vertical cross sectional view of a typewriter structure embodying the invention, some parts being shown in elevation, parts of the

typewriter not necessary to be disclosed to assist in understanding the invention being omitted;

Figure 2 is a detail view partly in section and partly in elevation drawn on an enlarged scale and showing key levers, type actions, and parts of a line lock mechanism constructed in accordance with the invention;

Figure 3 is a fragmentary detail view in elevation looking in the direction of the arrow 3 in Figure 1 and drawn on an enlarged scale;

Figure 4 is a fragmentary detail section taken on line 4—4 of Figure 1 and drawn on an enlarged scale; and

Figure 5 is a fragmentary view illustrating how type bars of prior art constructions may collide or effect "piling" at the end of a line, a fault of operation which is eliminated by the present invention.

The invention may be embodied in typewriting machines of various kinds, but, for the purposes of illustration, the invention is shown as being embodied in a Royal Standard typewriter including a main frame A and carriage B equipped with the usual platen C mounted on the frame for letter spacing and return travel.

A main frame A carries a fixed track rail 1 which supports an escapement frame 2. The fixed track rail 1, through the medium of ball bearings 3, supports a carriage track rail 4. Movement of the carriage for letter spacing is controlled by an escapement mechanism including an escapement wheel 5 which operates with suitable dogs (not shown) and an escapement pinion 6 meshing with a rack 7 secured to a bar 8 mounted on the carriage by means of arms 9 only one of which is shown. Mounted on the carriage is a longitudinally extending margin stop bar 10 on which a right margin stop 11 is mounted, preferably for adjustment, and is adapted to cooperate with a center stop 12 pivotally mounted on the main frame as at 13, a leaf spring 14 being arranged to urge the center stop to the operative or stopping position shown in Figure 1. The margin stop 11 does not contact directly with the center stop 12 when the carriage approaches the end of its letter spacing travel, but it engages first with a line lock lever 15 pivotally mounted on the center stop as at 16, the relation of the parts just prior to engagement of the right margin stop 11 with the line lock lever 15 being shown best in Figure 3. After the margin stop has engaged the line lock lever, further movement of the carriage and the margin stop will press the line lock lever against the center stop 12 so as to definitely arrest the

45

40

45

50

55

55

carriage and at the same time lock the printing mechanism against further operative movement in the manner to be described hereinafter.

The typewriter shown for the purposes of illustration includes a margin release key 17 pivotally mounted on a cross shaft 18 carried by the main frame. The key 17 is provided with a vertical arm 19 which is adapted to engage a lug 20 on a vertically extending lever 21 when the key 17 is depressed so as to rock the lever 21 to the left as viewed in Figure 1. A link 22 is pivotally connected at one end as at 23 to the lever 21, and at the other end is connected as at 24 to an arm 25 extending downwardly from the center stop 12. The arrangement is such that, when the key 17 is depressed, the lever 21 is rocked toward the left, thus pulling on the link 22 and swinging the downwardly extending arm 25 also to the left to swing the upper end of the center stop 12 toward the right, clear of the path of the margin stop 11, so as to permit the carriage to move beyond its normally fixed right margin position.

The typewriter shown may include suitable tabulating mechanism. As shown in Figure 1, a lower arm 26 on a pivoted lift lever 27 is positioned to be engaged by the downwardly extending arm 25 of the center stop 12 when the arm 25 is rocked to the left so as to rock the lift lever in a clockwise direction, causing an upper arm 28 to engage the bar 8 to lift the latter and the rack 7, thereby freeing the rack from the escapement pinion 6. The movement of the arm 25 and lift lever 27 required to effect escapement release for tabulating purposes is greater than the amount of movement of the arm 25 required to effect margin release by swinging the center stop clear of the right margin stop 11. The additional movement of the arm 25 required to effect escapement release for tabulating purposes may be obtained with the aid of a suitable device, not shown, but connected, for example, to the lever 21.

Typewriters embodying the present invention may be equipped with type actions of a known kind. Figure 1 shows one type action including a type bar 29 pivotally connected as at 30 to a type bar segment 31 supported on the main frame in the usual manner. The type bar is provided with a short arm 32 which is connected to a link 33 in turn connected to an intermediate lever 34 pivotally mounted as at 35. A link 36 is interposed between the intermediate lever 34 and a lever 37 pivotally mounted as at 38 adjacent the front of the typewriter. A link 39 is interposed between the lever 37 and a depressable key lever 40 pivotally mounted as at 48. The arrangement is such that depression of the key lever 40 will, by means of intervening lever and link connections, cause the type bar 29 to swing in a clockwise direction to printing position with reference to the platen C. A link 41 is connected between the intermediate lever 34 and the usual universal bar 42, which may be connected in a known manner to the escapement mechanism. A spring 43 interposed between the link 41 and a spring anchor plate 44 provides for the desired type action tension and assists in returning the type bar 29 to its normal position. A cushioning key lever rest 45 carried by a part 46 mounted on the main frame is positioned above the key levers 40, and the usual type bar rest 47 serves to support the type bar 29 when it is in its state of rest position.

It will be understood that typewriters embodying the invention will include the usual number of complete type bar actions. Figures 1 and 2 show one additional type action which includes

parts similar in construction and arranged correspondingly to the parts of the type action described above, the parts of the second type action illustrated being designated by reference numerals the same as those designating corresponding parts of the type action described, with the exception that the reference numerals designating parts of the second type action are primed.

The parts thus far described are of known construction and relative arrangement, and they do not per se constitute the present invention. The present invention resides in the provision of novel and improved mechanism for controlling or locking the type actions against movement when the carriage reaches or approaches the end of its letter spacing travel, and the cooperative arrangement of such mechanism with some of the conventional parts which already have been described.

In accordance with the invention, a typewriter is provided with line lock mechanism responsive to carriage travel for positively locking any one of the key levers or type bars against operative movement irrespective of whether any other key lever is in elevated or depressed position. In the illustrative embodiment, the line lock lever 15, pivotally mounted on the center stop as at 16, is provided with a downwardly extending arm 48 which is connected as at 49 to a link 50 in turn pivotally connected as at 51 to a lever generally designated 52 mounted to rock about pivots 53-53 on the main frame A. The lever 52 includes a horizontal upper arm 54, and a horizontal lower arm 55 joined by a vertically extending plate portion 56. A spring 57 interposed between the upper arm 54 and the frame A urges the line lock lever to the position shown in Figure 3, wherein the upper portion of the line lock lever is disposed out of contact with the center stop 12. Movement of the parts under the urge of the spring 57 is limited by engagement of a stop projection 58 on the lever 52 with the main frame A. A link 59 is pivotally connected at its rear end as at 60 to the lower arm 55 on the lever 52, and at its front end is pivotally connected as at 61 to a stop plate 62 which is adjustably or pivotally mounted as at 63 for rocking movement. Normally, the plate 62 is in the position shown in Figure 1, wherein its upper edge 64 is below and in front of or clear of the paths of movement of abutments on the bottoms of the key levers, two such abutments 65 and 65' on the key levers 40 and 40' respectively in the planes of the key levers being shown. The top corner edge of the plate 62, which leads when the plate is rocked clockwise as viewed in Figures 1 and 2 to line locking position, is formed as a sharp line edge 64a. The abutments of all of the key levers are aligned in parallelism with the pivotal axis of the plate 62, so that the plate 62 may cooperate as a common stop device with each and all of the abutments. In accordance with the invention, the abutments are so shaped as to permit movement of the stop plate 62 to completely operative position under key lever abutments, even after one of the abutments already has moved downwardly past the top of the stop. In the form shown, the abutment 65 is formed with a lower horizontal edge or surface 67 and with a receding or inclined surface or edge 68 which extends upwardly and inwardly toward the body of the abutment and intersects the bottom edge 67 to form conjointly therewith an acute angle having a sharp line edge 67a at its vertex. The abutment 65' on the key lever 40' and 75

the corresponding abutments on key levers not shown are of similar construction.

In operation, the various parts will be in the positions shown in Figure 1 before the carriage approaches the end of its letter spacing movement as determined by the setting of the margin stop 11. Assuming that the carriage then reaches a position one letter space away from the limit of its travel, and assuming that the key lever 40 is then depressed, the carriage will be moved to the left through the remaining letter space distance, and will cause the margin stop 11 to engage the line lock lever 15 (see Figure 3) so as to move the upper end of the line lock lever toward the center stop. Such movement of the line lock lever will, by means of the link 50, the lever 52, and the link 59, rock the stop plate 62 in a clockwise direction as viewed in Figures 1 and 2, bringing it to the position shown in Figure 2, and positioning its top edge 64 under the abutments of all of the key levers, with the exception of the key lever 40 depressed just prior to the final letter space movement of the carriage. Because of the shape of the abutment 65, the plate 62 is permitted to move under the abutment 40 and corresponding abutments on the other key levers (not shown), even while the key lever 40 is held in depressed position as shown in Figure 2. Thus, if the operator should attempt to depress another key lever, say, the key lever 40', before releasing the key lever 40, depressing movement of such other key lever is positively blocked and prevented by the stop plate 62, which has been moved to its completely operative position. Movement of the stop plate to its completely operative position is permitted in this instance by the inclination of the receding edge 68, which makes it possible for the upper part of the stop plate to move into overlapping relation with respect to the abutment edge 68.

When the key lever 40 is released, it will be returned to its normal position in the usual manner without interference by the stop plate, the play or lost motion in the connections between the line lock lever and the stop plate 62 permitting the inclined edge 68 of the abutment to cam the plate 62 in a counterclockwise direction, in turn permitting the abutment 65 to move upwardly to a position corresponding to the position of the abutment 65' shown in Figure 2. With the arrangement described, it is impossible to effect operative movement of any type action after depression of one key lever effects movement of the carriage to its margin stop position.

The mechanism disclosed herein embodies the invention in the form now preferred, but it is apparent that changes may be made in the construction and arrangement of the parts without departing from the invention as defined in the claims.

I claim:

1. In a typewriter; a travelling carriage; a plurality of key levers; and line lock mechanism for said levers comprising a plurality of abutments respectively rigid with and depending from the key levers, the abutments being horizontally aligned with each other and each having a horizontal bottom edge and a receding edge portion inclined directly from its juncture with said bot-

tom edge upwardly and inwardly toward the juncture of the abutment with the key lever, said receding edge portion intersecting said horizontal bottom edge and forming therewith an acute angle with a sharp line edge at its vertex, a stop plate pivoted to rock about a horizontal axis below the abutment bottom edges, the plate being movable to a position in which its top edge is disposed out of the downward path of said abutments, and to a second position in which its top edge is disposed below and in the path of said abutment horizontal bottom edges, the plate being movable to said second position and with its top edge over the receding edge of an abutment on a key lever depressed previously to such movement of the plate, said plate having a sharp line top corner edge positioned to be leading when the plate is being moved to said second position whereby chance of blocking of the plate's movement to said second position by a partially depressed key lever is minimized and substantially eliminated, and means responsive to carriage travel for moving said plate to said second position.

2. In a typewriter; a frame; a travelling carriage; a plurality of key levers; and line lock mechanism for said levers comprising a plurality of abutments respectively rigid with and depending from the key levers, the abutments being horizontally aligned with each other and each having a horizontal bottom edge and a receding edge portion inclined directly from its juncture with said bottom edge upwardly and inwardly toward the juncture of the abutment with the key lever, said receding edge portion intersecting said horizontal bottom edge and forming therewith an acute angle with a sharp line edge at its vertex, a stop plate pivoted to rock about a horizontal axis below the abutment bottom edges, the plate being movable to a position in which its top edge is disposed out of the downward path of said abutments, and to a second position in which its top edge is disposed below and in the path of said abutment horizontal bottom edges, the plate being movable to said second position and with its top edge over the receding edge of an abutment on a key lever depressed previously to such movement of the plate, said plate having a sharp line top corner edge positioned to be leading when the plate is being moved to said second position whereby chance of blocking of the plate's movement to said second position by a partially depressed key lever is minimized and substantially eliminated, a line lock lever mounted on said frame, a part on said carriage adapted to engage and operate said line-lock lever when the carriage reaches the end of letter-spacing travel, and lever and link connections between the line-lock lever and the plate for moving said plate to said second position in response to movement of the line-lock lever by said carriage part, there being sufficient play or lost motion in said lever and link connections to permit the receding edge on the abutment of the previously depressed key lever to cam the stop plate clear of said receding edge and thereby permit said previously depressed key lever to rise during continued engagement of said carriage part with said line-lock lever.

HENRY JOSEPH HART.
